UNITED STATES PATENT OFFICE.

ALFRED KILE ALBERT, OF FORESTBURG, TEXAS.

DESIGN FOR A KNIFE.

SPECIFICATION forming part of Design No. 27,033, dated May 11, 1897.

Application filed February 17, 1897. Serial No. 623,883. Term of patent 7 years.

To all whom it may concern:

Be it known that I, ALFRED KILE ALBERT, a citizen of the United States, residing at Forestburg, in the county of Montague and State 5 of Texas, have invented a certain new and original Design for Knives; and I do hereby declare the following to be a full, clear, and exact description of the invention, such as will enable others skilled in the art to which 10 it appertains to make and use the same.

My invention relates to designs for knives; and it consists in details which will be hereinafter fully set forth, and illustrated in the accompanying drawings, in which—

15 Figure 1 is a side view of my invention complete. Fig. 2 is a view showing the edge thereof.

Referring to the drawings, 1 represents the blade portion of the knife, while 2 represents 20 what is practically a continuation of the blade shaped to form part of the handle.

Section 2, after extending a sufficient length

to provide the length of the handle, is bent upon itself, forming the curved section 3, and then extends parallel with the section 2, forming the section 4, which latter terminates in the curved shield or guard 5.

It will be observed that my design represents a knife formed of one piece of suitable material which may be employed to subserve 30 different purposes. The object in thus providing the curved terminal is to form a shield which will protect the hand from contacting with the blade.

What I claim as new, and desire to secure 35 by Letters Patent, is—

The design for a knife substantially as herein shown and described.

In testimony whereof I affix my signature in presence of two witnesses.

ALFRED KILE ALBERT.
